UNITED STATES PATENT OFFICE.

WILLIAM C. WINFIELD, OF WARREN, OHIO, ASSIGNOR TO THE WINFIELD MANUFACTURING COMPANY, OF SAME PLACE.

DESIGN FOR A FAUCET.

SPECIFICATION forming part of Design No. 22,570, dated June 27, 1893.

Application filed January 3, 1893. Serial No. 457,166. Term of patent 7 years.

To all whom it may concern:

Be it known that I, WILLIAM C. WINFIELD, a citizen of the United States, residing at Warren, in the county of Trumbull and State of Ohio, have invented and produced a new and original Design for Faucets, of which the following is a specification, reference being had to the accompanying drawing, forming a part thereof.

10 The essential features of this design are the barrel having a substantially circular cross-section, a plug-receiving projection rising from the barrel in curved lines which are essentially segments of circles, a flared cavity 15 around the top of this projection, a groove extending thence down the projection and into the outlet of the barrel, and a cruciform plug handle of curvilinear cross-section.

The design is illustrated in the accompanying drawing which shows my faucet in perspective view.

A, is the barrel, of substantially circular cross-section, having the outlet a.

2, is a plug-receiving projection rising in curved lines from the upper portion of the 25 barrel, and having the band 3 and flared cavity 4.

5, is the valve stem, and 8 the handle, the two being cruciform or of T-shape in outline and of curvilinear cross-section. 30

6, is a groove extending from the cavity 4 down the projection and along the outlet of the barrel and disappearing in the hole 7 in said outlet.

What I claim is—35 The design for a faucet, substantially as shown and described.

WILLIAM C. WINFIELD.
